US0D1106968S

(12) **United States Design Patent** (10) **Patent No.:** **US D1,106,968 S**
(45) **Date of Patent:** **** Dec. 23, 2025**

(54) **FEMALE CONNECTOR**

(71) Applicant: **Yuanzhi Li**, Guangdong Province (CN)

(72) Inventor: **Yuanzhi Li**, Guangdong Province (CN)

(**) Term: **15 Years**

(21) Appl. No.: **29/890,009**

(22) Filed: **Apr. 19, 2023**

(51) **LOC (15) Cl.** **13-03**

(52) **U.S. Cl.**

USPC **D13/147**

CLAIM

The ornamental design for a female connector as shown and described.

DESCRIPTION

FIG. 1 is a perspective view of a female connector showing my new design;

FIG. 2 is a front elevational view thereof;

FIG. 3 is a top plan view thereof;

FIG. 4 is a left side elevational view thereof;

FIG. 5 is a rear elevational view thereof;

FIG. 6 is a right side elevational view thereof; and,

FIG. 7 is a bottom plan view thereof.

The broken lines in the drawings depict portions of the female connector that form no part of the claimed design.
